UNITED STATES PATENT OFFICE.

FREDERICK W. GROSS, OF COLUMBUS, OHIO.

SILO.

1,340,890.

Specification of Letters Patent. Patented May 25, 1920.

Application filed May 22, 1919. Serial No. 298,960.

To all whom it may concern:

Be it known that FREDERICK W. GROSS, a citizen of the United States, residing at Columbus, in the county of Franklin and State 5 of Ohio, has invented certain new and useful Improvements in Silos, of which the following is a specification.

This invention relates to improvements in silos and has particular reference to an 10 improved door construction for silos generally.

The object of the present invention is to provide a durable, inexpensive and easily 15 operated mounting for silo doors, said mounting being so constructed that when the doors are positioned to close their respective openings, said mountings may be employed to securely lock the doors against movement, and when said doors are opened, 20 said mountings serve to facilitate the opening operation by guiding the doors in their course of travel to an open position and in sustaining said doors in said latter position.

Another object of the invention resides 25 in a door mounting of the aforesaid character, whereby when the doors occupy closed positions, said mountings may serve in the capacity of ladders.

With these and other objects in view, the 30 invention accordingly consists in the novel features of construction, combination of elements and arrangement of parts, herein-after to be fully described and have the scope thereof pointed out in the appended 35 claims.

In the accompanying drawing:

Figure 1 is a fragmentary front elevation of a silo and illustrating the application 40 of the door mounting comprising the present invention thereto, said mounting being shown in the position of retaining a door in a closed position.

Fig. 2 is a vertical longitudinal sectional view taken along the line 2—2 of Fig. 1.

Fig. 3 is a horizontal sectional view, taken 45 along the line 3—3 of Fig. 1 and illustrating the door member in a closed position.

Fig. 4 is a similar view, disclosing the door member in its open position, and,

Fig. 5 is a detailed perspective view of 50 the mounting *per se*.

Similar characters of reference denote like and corresponding parts throughout the several views of the drawing.

Referring more particularly to the details 55 of the invention, as the latter have been ex-

emplified in the drawing, the numeral 1 designates the outer wall of a so called staved silo, the latter being of the usual cylindrical form and its wall is composed of the usual 60 tongue and grooved sections 2, the latter being matched to form the circular contour of the silo. The silo 1 in this instance is provided with vertical frame members or jambs 3, which extend parallel with vertically 65 aligned door openings 4 of the silo and said frame members 3 are spaced by means of transverse sills 5, which in conjunction with the frame members serve to define the several door openings 4. Adapted to cover the 70 openings 4 are a plurality of door members 6, which latter in the form disclosed in the drawings each consists of a back section 7 which is strengthened by means of spaced parallel bars 8 which are adapted to lie 75 within the coöperative opening 4 when the door member for said opening is in a closed position. The margins of the sections 7 are in this instance disposed to engage with the rear surfaces of the frame members 3 or the 80 sills 5, so that outward movement on part of the door members will be precluded.

To lock the door members in their closed positions, each of said members is provided with a mounting 9 of improved construction. 85 The mounting in this instance consists of a pair of twisted rod members 10 for each of the doors 6, and said members are each formed to comprise a straight lower portion 11, a perpendicular end portion 12, a bearing 90 portion 13 disposed to lie parallel with the lower portion 11, an offset handle extremity 14 and a second bearing portion 15, disposed in alignment with the portion 13. Said bearing portions 13 and 15 are slidably mounted 95 for horizontal movement within bearings 16 rigidly mounted upon the bars 8, and the lower portion 10 has its free extremity slidably mounted within fixed bearings 17 provided upon one of the frame members 3. 100

In operation, when it is desired to close the door member 6 and to retain the same in such position, the members 10 are reciprocated to the left, so that their end portions 12 will overlie the frame member 3 opposite 105 to the frame member upon which the bearings 17 are provided. When thus positioned, the rod members 10 will prevent inward movement on part of the doors 6 so that the latter will be securely retained in 110 their active positions. It will be observed in this connection that the opposite ends of

the rod members 10 overlap the respective frame members 3, thus effectively preventing inward movement on part of the doors. When thus positioned, the handle extremities 5 14 of said rod members project horizontally outward, and by being thus formed, the same may serve in the capacity of a ladder, thus enabling an operator to gain access to all parts of the silo 1. To move the door 10 to an open or inactive position, the rod members 10 are reciprocated bodily in the direction of the arrow B so that their end portions 12 will be freed from engagement with the associated frame member 3. Then 15 by forcing the door member 6 inwardly, the lower portions of the rod members 10 will be permitted to revolve in their bearings 17 so that the door 6 will drop to a slight extent, this extent being governed by the extent 20 engagement of the extremities 14 with the outer face of the door. When in this position, said door member will lie within the interior of the silo whereby continued pressure in the direction of the arrow B will cause said rod members and their associated door 6 to slide to a position completely clearing the door opening 4 whereby free and unobstructed access to the latter may be obtained. It will thus be apparent that the 25 silo mounting comprising the present invention is of a relatively simple nature, capable of being applied to silo doors now in use and is reliable and efficient in operation. When closed, the door members 6 will be 30 firmly supported against movement by the coöperation existing between the rod members 10 and the frame members 3, and when so positioned, said mounting may be effectively used in the capacity of a ladder. 35 Then, to open the door, the latter may be released by merely sliding the members 10 a limited distance to free their locking portions 12 from engagement with the adjacent frame 3. This permits the door member to

automatically gravitate to a position within 45 the silo so that the same may be forced to one side of the door opening 4 without interference on part of the wall of the silo.

In view of the foregoing, it is believed that the operation and construction of the 50 invention will be apparent to those versed in the art, and therefore a more detailed explanation has been accordingly omitted.

What is claimed is:

1. In a silo, the combination with the wall 55 thereof, having a doorway, of a door adapted to be fitted within said doorway, a mounting for said door comprising a pair of slidably supported elements, said elements including lower portions having the free ends 60 thereof slidably mounted in bearings carried by the frame of said doorway, upper portions formed with said elements and disposed to lie parallel with said lower portions, said upper portions being slidably 65 mounted within bearings carried by said door, and end portions formed with said elements and disposed to connect said upper and lower portions, whereby when said door occupies a closed position, said end portions 70 may be reciprocated to lock the door against inward movement.

2. In a silo, a door frame formed in said silo and having door openings formed therein, a plurality of door members capable of 75 occupying said openings, a mounting for said door members comprising for each door member a pair of rod elements, said elements including lower extremities slidably mounted within bearings carried by said frame, an 80 upper portion slidably mounted in bearings carried by said door member, and a connecting portion capable of overlapping said door frame to maintain the door member in a closed position and a handle formed upon 85 the upper portion of each of said elements.

In testimony whereof I affix my signature.

FREDERICK W. GROSS.
